STOP MECHANISM FOR RELIEFGRAPHS.

1,186,972.

Specification of Letters Patent. Patented June 13, 1916.

Application filed September 2, 1913. Serial No. 787,770.

To all whom it may concern:

Be it known that I, FRANK DE MINICO, a citizen of the United States, and a resident of New York, in the county of New York and State of New York, have invented certain new and useful Improvements in Stop Mechanism for Reliefgraphs, of which the following is a specification.

This invention relates to stop mechanisms 10 for reliefgraphs. Such for instance as is partially shown in Letters Patent of the United States No. 875,679, granted to Frederick H. Alling January 7, 1908.

The object of my improvements is to provide means for stopping the die shafts of 15 such a machine as that of the patent to Alling without jar or pound and for positively locking those shafts in their stopped positions.

To these ends my improvements comprise 20 means illustrated in their preferred embodiment in the accompanying drawings wherein—

Figure 1 is a side elevation partly in section of so much of a reliefgraph as will suffice to illustrate my improvements. Fig. 2 is a fragmentary sectional rear elevation on line 2—2 of Fig. 1. Fig. 3 is a rear elevation of a portion of what is shown in Fig. 20 2 but showing the parts in a different relation to each other. Figs. 4 and 5 are fragmentary plan views of a portion of what is shown in Fig. 1, illustrating some features of the operation of my improvements.

In machines of the character to which the present improvements pertain, it is required 35 that the pair of spindles or die shafts which are geared together be suddenly stopped when rotating at high speed at any one of a given plurality of predetermined positions and maintained in that position of rest during the major portion of one revolution of the lever actuating crank shaft.

Heretofore it has been customary in machines of this class to employ a stop arm rigidly fixed to one of the die shafts for engagement with the selected stop pin. While this arrangement has been found serviceable, the blow of the suddenly stopped rigid arm against the rigid pin is obviously severe and the present improvements are directed toward, among other results, a reduction of the severity of that blow.

Before describing the invention in detail, 55 I desire to have it understood that the in-

vention is not limited to the particular construction and arrangement of parts which I have illustrated and shall hereinafter describe, and that various changes may be made in the mechanism shown without departing from the spirit or scope of the invention, and that the phraseology which I employ is for the purpose of description and not of limitation.

In the main frame 3 of the machine are 60 rotatably mounted upper die shaft 4 and lower die shaft 5, having fixed thereto intermeshing spur gears 6 and 7 respectively. The upper die shaft 4 is longer than the lower die shaft 5, and projects rearwardly 65 to the left a distance sufficient to present for engagement with pulley 8, friction clutch 9, fixed by means of screw 10 to said rearwardly projecting end. Pulley 8 is supported in a suitable bearing in upstanding 70 ear 11 fixed to the rearward portion of main frame 3. Said pulley 8 is provided with a suitable groove for belt 12 by which it is constantly driven from some suitable source 75 of power not shown. Connected with pulley 8 is a pair of diametrically opposite eccentrics 56 and 57 which by means of connecting rods 13 and 14 transmit oscillatory motion to lower lever 15 and upper lever 16, all respectively. These levers operate in a 80 well known manner the dies in the die heads not shown. Between gear 6 and friction clutch 9, arranged concentrically about shaft 4 is a bank of stop pins as 17 arranged to be actuated in parallelism with said shaft 85 4 by suitable key levers as 50. Said stop pins as 17 may be conveniently mounted to slide in disks 18 and 19 suitably supported from frame 3 by means not shown.

Oscillatably mounted on shaft 4 between 90 gear 6 and disk 19 is stop arm 20. The oscillatory movement of said stop arm relatively to shaft 4 is limited by abutments as 21 and 22 on said arm in engagement with coacting abutments 23 and 24 projecting 95 from gear 6 in the path of the abutments on said arm. For resistance to endthrust, the source of which will appear later herein, and to minimize the friction caused by said endthrust, I preferably employ a ball bearing as 25 between gear 6 and arm 20. The hub portion of arm 20 is provided with a rearwardly reaching sleeve 26 having therein a helical cam slot 27 for engagement with cam roll 28 mounted on pin 29 inreaching 100 105 110

from sleeve 30. Said sleeve 30 is mounted for endwise movement on shaft 4, and is constrained to rotation with that shaft by roll 31, pinned to said shaft in engagement with slot 32 in said sleeve 30. Said sleeve is chambered at its outer left hand end, Fig. 1, for the reception of spring 33 for urging said sleeve to the right, and through the instrumentality of roll 28 in engagement with cam slot 27, for urging arm 20 to its normal position of, for instance, Figs. 3 and 5. To the outer end of said sleeve 30 is fixed collar 34 for engagement with trip pin 35 of the clutch mechanism in pulley 8. Said clutch mechanism is provided to cause the eccentrics in engagement with connecting rods 13 and 14 to make one revolution and then stop, as fully set forth in the above mentioned patent to Alling. Said collar 34 is slotted at 36 and 37 to permit endwise movement thereof without interfering with friction clutch 9.

The eccentrics 56 and 57 for actuating connecting rods 13 and 14 respectively, are not rigidly secured to pulley 8 but are normally loose therefrom, a mechanism being provided to rigidly connect said eccentrics with said pulley and the operation of which is controlled by the arrest of shaft 4. Said eccentrics are integral with shaft 45, rotatable in sleeve-like bearing member 46, in-reaching from ear 11 of frame 3. Said member 46 is preferably provided with a friction sleeve 47 on which pulley 8 is rotated. A retaining plate 48 is threaded on the reduced end of bearing member 46 and engages a shoulder portion 49 in the recessed face of pulley 8. Said recessed face of pulley 8 is provided with ratchet teeth 51. On the hub of retaining plate 48 is pivotally mounted a cam 52 and rigidly connected to the reduced end of shaft 45 is arm 53. A pawl 54, pivotally mounted at 55 on arm 53, and the heel of which may come into engagement with ratchet teeth 51 of pulley 8, is normally held out of such engagement by cam 52. Trip pin 35 is yieldably supported on arm 53 and is arranged to engage yieldable cam 52. Thus, when shaft 4 is arrested and sleeve 30 is moved to the left, collar 34 will cause trip pin 35 to engage cam 52 and move said cam out of the plane of pawl 54 on arm 53, thus causing the heel of said pawl to engage ratchet teeth 51 of pulley 8 and shaft 45 to make one revolution. As this clutch mechanism is well known in the art and is no part of the present improvements, a more detailed description and showing is not deemed necessary.

60 For locking gear 6 in fixed position after that gear has been stopped by the engagement of stop arm 20 with one of the stop pins as 17, I provide lock arm 38 pivoted at 39 in main frame 3 and having teeth as 40 for engagement with the teeth of said gear.

Said lock arm is urged to such engagement by means of pull spring 41. Said arm is normally restrained from such engagement by means of push pin 42 adjustably fixed in ear 43 out-standing from upper lever 16. When said lever is in its downward position of rest, as shown by dotted lines in Fig. 1, the lower end of pin 42 will engage heel 44 of lock arm 38 thereby holding said lock arm out of engagement with gear 6 against the pull of spring 41.

The operation of my improved stop mechanism is as follows: The finger end of one of the key levers as 50 being depressed, its co-acting stop pin 17 will be projected into the path of arm 20, Fig. 1, and that stop arm in its rotation with shaft 4 will presently engage that stop pin and be stopped thereby. The inertia of shaft 4 and the parts fixed thereto, will tend to cause that shaft to continue its rotation and such rotation will be continued until abutment 23 of gear 6 engages abutment 21 of the stop arm. This rotation of shaft 4 from the time of the engagement of the stop arm with pin 17, until the engagement of abutment 21 of that stop arm with the abutment 23 of the gear will be under constraint, that constraint being caused by the movement of cam slot 27 on its roll 28 against the pressure of spring 33, and which constraint will tend to stop shaft 4, thereby materially lessening the blow between abutments 21 and 23. The limited rotation of shaft 4 from the position of Fig. 3 to that of Fig. 2 will cause sleeve 30 to move endwise to the left from the position of Fig. 5 to that of Fig. 4, thereby causing collar 34 to engage trip pin 35, whereby the eccentrics on shaft 45 of the clutch mechanism will be caused to make one revolution, moving die levers 15 and 16 first outwardly to the positions of Fig. 1, and then inwardly to their normal positions. As said lever 16 moves upwardly to the position of Figs. 1 and 2, lock arm 38 is released to move downwardly toward and into engagement with the teeth of gear 6, Fig. 2, whereby said gear and gear 7, meshing therewith, are locked against rotation and held rigidly in their positions of rest. Upon the descent of arm 16, pin 42 will again engage heel 44 of lock arm 38, thereby disengaging that arm from gear 6; pin 17 being simultaneously or previously withdrawn, arm 20 is urged by spring 33 to its normal position relatively to gear 6 and sleeve 30 returns to its normal position of Fig. 5. Gear 6 and shaft 4 are then free to revolve until another stop pin is projected into the path of stop arm 20 when the described operation is repeated.

I claim:

1. Stop mechanism including in combination, a rotating pulley, a rotatable shaft yieldably driven therefrom, a stop arm os- 130

actuated locking arm for locking said shaft against rotation, means on said shaft for engagement with said locking arm, and means governed by the oscillatable arm for releasing said locking arm.

10. Stop mechanism including in combination, a rotating pulley, a rotatable shaft yieldably driven therefrom, a stop arm rotatably mounted on said shaft, means for 10 limiting the rotary movement of said shaft relatively to said stop arm, a sleeve slidably mounted on said shaft, means for preventing rotation of said sleeve relatively to said shaft, means for urging said sleeve toward said stop arm, means on said arm coacting with means on said sleeve for sliding said sleeve relatively to said shaft during the

limited rotation of said shaft relatively to said stop arm, a one-revolution clutch, means governed by the sliding of said sleeve for actuating said clutch, an oscillatable arm, means for oscillating said arm from said clutch, a gear fixed to said shaft, a spring-actuated locking arm for engagement with said gear, and means governed by the oscillatable arm for releasing said locking arm. 20 25

Signed at New York, in the county of New York and State of New York, this 30th day of August, 1913, before two subscribing witnesses.

FRANK DE MINICO.
